(57) **CLAIM**

The ornamental design for an image scanner for a computer, as shown and described.

DESCRIPTION

FIG. 1 is a front perspective view of an image scanner for a computer showing my new design;

FIG. 2 is a front view thereof;

FIG. 3 is a rear view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another front perspective view thereof with the operating cover on the front side in the open position;

FIG. 9 is a rear perspective view thereof with the operating cover on the rear side in the open position; and,

FIG. 10 is a perspective view thereof with a paper feed tray on the left side and a catch tray on the right side of the scanner are extended.

The broken line in the drawings is for illustrative purpose only and forms no part of the claimed design.
